MANUFACTURE OF SHOES

Raymond E. Hopkins, Weymouth, Mass., assignor to United Shoe Machinery Corporation, Borough of Flemington, N. J., a corporation of New Jersey

Application October 19, 1937, Serial No. 169,814

4 Claims. (Cl. 12—142)

This invention relates to improvements in shoes and shoe parts and to improved methods of making shoes. The invention is herein illustrated with reference to its application to shoes having no inner sole members in their foreparts, such shoes being commonly referred to as single-sole shoes.

Single-sole shoes have the advantage of being more flexible than shoes having inner and outer soles which are firmly secured together in accordance with conventional methods of shoemaking. In single-sole shoes, as ordinarily constructed, however, the upper has a tendency to pull away from the margin of the tread sole because of the absence of an insole or other element overlying the inturned lasting allowance of the upper and providing internal support for that part of the upper which is immediately above the lasting allowance, and thus the portion of the upper referred to soon loses the shape initially imparted to it by the edge of the last bottom.

Objects of the present invention are to overcome the undesirable condition just referred to and to provide means, in a single-sole shoe, for permanently preserving the contour of the upper in the region where it was caused to break over the edge of the last bottom in the lasting operation. In one embodiment of the invention herein illustrated the shoe comprises a tread sole, an upper having an inturned margin secured to the tread sole, and a sock lining secured to the tread sole, the sock lining being soft and limp throughout its greater portion but having a marginal portion of substantial width which is relatively stiff and provides internal lateral support for the portion of the upper immediately adjacent to the inturned margin thereof. The illustrated sock lining is cut from soft, limp leather having a grain surface at the side which is to engage the foot and a flesh surface at its opposite side. The stiffening of the marginal portion of the sock lining may be accomplished by applying a coating of liquid stiffening material to the flesh side of the sock lining and allowing it to penetrate well into the substance of the lining without, however, striking through to the grain surface thereof, so as to mar or stain that surface.

A shoe to which my improved sock lining is to be applied may be made without an insole member in its forepart, as herein shown, and the tread sole may be secured in any well-known manner as by means of cement or stitches to the inturned lasting allowance of the upper after the shoe has been otherwise completed. The sock lining is inserted within the shoe and is secured in place

by means of adhesive such as rubber cement. Preferably, the adhesive is supplied only to that portion of the sock lining which is within the stiffened margin thereof in the forepart of the lining so that the unstiffened portion only of the forepart lining will be secured to the tread sole of the shoe. Thus, the stiffened marginal portion will remain unattached to the shoe bottom and this will not impart even the slightest degree of stiffness to the latter. The cementing of the unstiffened portion of the forepart of the sock lining to the shoe bottom, however, will result in the lining being held securely in place in such a manner that its stiffened marginal portion will effectively resist any edgewise thrust tending to distort it and will thus act as an outline preserving element affording the desired internal support for the upper so as to retain the shape of the latter and prevent it from pulling away from the edge of the tread sole. In cases where the sock linings are to be used in shoes of the open-shank sandal type or other shoes the uppers of which are cut away so as to expose edge portions of the shoe bottoms, it is preferred to stiffen the margins of the sock linings with a liquid containing a colored stiffening substance and thereby to color and consolidate the fibers of the leather at the edges of the linings so that the edges will present a smooth and finished appearance where they are exposed to view in the finished shoes.

Considered in another aspect invention is to be recognized as residing in an improvement in shoemaking which consists in making a shoe without an insole in its forepart, providing a sock lining of soft, limp material having its marginal portion only impregnated with a stiffening substance and thereby rendered relatively stiff, applying adhesive to one side of that portion only of the sock lining which is located inwardly of its relatively stiff marginal portion, inserting the sock lining within the shoe with its adhesive treated surface facing the bottom of the shoe, and pressing the sock lining into intimate contact with the shoe bottom thereby securing the unstiffened portion only of the sock lining to the shoe.

The invention will be explained with reference to the accompanying drawing, in which

Fig. 1 is an elevational view of a portion of a coating machine illustrating the application of a stiffening solution to the marginal portion of a sock lining;

Fig. 2 is a perspective view of a sock lining the

marginal portion of which has been stiffened in the forepart only of the lining;

Fig. 3 is a perspective view of a sock lining the marginal portion of which has been stiffened 5 in the shank as well as in the forepart;

Fig. 4 is a fragmentary perspective view on an enlarged scale of a sock lining to which cement has been applied preparatory to securing the sock lining in place within a shoe;

10 Fig. 5 is a perspective view of a single-sole shoe in the course of manufacture;

Fig. 6 is a cross-sectional view of a shoe as it appears after a sock lining has been applied;

15 Fig. 7 is a fragmentary cross-sectional view of the shoe showing stitches for securing the tread sole to the upper; and

Fig. 8 is a perspective view of an open-shank shoe having my improved sock lining therein.

In the manufacture of my improved shoe I 20 employ a full length sock lining 12 which is composed of soft, limp material, preferably upper leather such as kid, and which has a smooth grain surface 14 at the side which is to be next to the foot and a soft flesh surface 16 at the opposite 25 side. The sock linings are of the usual shape and are formed from sheet stock by die-cutting operations which are carried out in the usual manner. To adapt the sock linings to serve as means for supporting the uppers so that the latter will 30 have no tendency to pull away from the soles of single-sole shoes I prepare the linings by applying to the marginal portion only of each lining at the flesh side thereof a coating 18 of a suitable liquid stiffening substance, such for 35 example as a solution of rosin, the coating being applied at the forepart only of the sock lining, as indicated in Fig. 2, or at the forepart and shank portions, as indicated in Fig. 3. Preferably, the stiffening solution employed is of such a 40 character that it will strike inwardly from the flesh surface of the lining and will penetrate nearly but not quite to the grain surface thereof, it being desirable to leave the grain surface entirely unaffected by the solution so as to avoid 45 staining or marring it in such a manner as to detract from its appearance in the shoe. The solution, however, will impregnate the sock lining sufficiently so that when it has become dry it will stiffen the marginal portion of the lining so 50 as to enable it to perform its intended function. As shown, the sock lining is stiffened throughout a marginal area of substantial width so that after the lining has been secured in place within the shoe its marginal portion will not be readily 55 distorted by any edgewise pressure applied thereto.

The stiffening coating may advantageously be applied to the sock lining by means of a coating machine such as that disclosed in United States Letters Patent No. 1,851,162, granted March 29, 60 1932, upon application of J. W. Cosgrove. In the use of such a machine, as illustrated in Fig. 1, the stiffening solution is applied to the sock lining by means of a roll 20 while the marginal 65 portion of the lining is supported upon a feed roll 22 and while the lining is guided and located relatively to the roll 20 by means of an edge gage 24.

Marginally stiffened sock linings prepared as 70 herein described may be applied to single-sole shoes made in accordance with any well-known method of manufacture, an example of a suitable method being that disclosed in United States Letters Patent No. 2,068,175, granted December 8, 75 1936, upon application of J. C. Lisbon, Sr. In ac-

cordance with this particular method and as illustrated in Fig. 5, an upper 28 is assembled upon a last 30 having upon its bottom face a temporary forepart lasting piece 36 provided with marginal lasting ribs 38 and having also a heel 5 and shank piece 32 which has marginal lasting ribs 34, and the feather portions of which have been previously roughened and coated with cement such as pyroxylin cement which has been allowed to dry. The margin of the upper is next 10 treated with cement which in the shank portion is introduced between the several layers or plies of the upper and also to the inner side of the lining. In the portion of the forepart where the lasting piece 36 is located the cement is applied 15 only between the plies of the upper. The cement on the heel and shank piece is then activated by a suitable solvent thus preparing the shoe for the lasting operation. In lasting the upper its marginal portions are wiped inwardly against 20 the lasting ribs 34 and 38 and are temporarily secured to the ribs by means of staples, the staples serving to hold the upper during the setting of cement. After the cement has become set upper trimming operations are performed as a result of 25 which excess upper materials and the lasting ribs 34 are removed in the shank portion of the shoe while in the forepart the overlasted upper is cut in such a way as to separate the portions which are secured to the ribs 38 from those which overlie 30 the bare surface of the last bottom. Thereafter, the temporary forepart lasting piece 36 is removed, thus removing also the ribs 38 and the excess portions of the upper materials and exposing 35 the bare last bottom at the forepart of the last. The overlasted marginal portions of the upper are next prepared in the usual manner for the attachment of a tread sole 40 thereto by means of cement, the tread sole is laid in position on the shoe bottom and pressure is applied 40 to force the sole against the cemented portions of the upper, the pressure being maintained until the cement has set to cause the tread sole to become permanently attached to the shoe bottom. The tread sole may, if desired, be attached by 45 through-and-through stitches as shown in Fig. 7. It will be noted that the finished shoe has no insole member in its forepart thus rendering it much more flexible than if it had both insole and outsole members in its forepart.

If cement is employed as the only means for 50 attaching the tread sole to the shoe, the sole will have been permanently attached and the shoe completed, except for the application of the sock lining, before the last is removed from the shoe. 55 If through-and-through stitches are to be employed to secure the tread sole to the shoe, the last, of course, will have to be removed before the stitching is done. In either case the sock lining is not applied until after the last has been removed from the shoe and the shoe has been otherwise completed. A quantity of sock linings, the marginal portions of which have previously been stiffened as hereinbefore explained, are coated at their flesh sides with cement, for example, rubber latex, at some time prior to the time when they are to be used and the cement is allowed to set until it has become tacky so that it will be in a condition to adhere readily to the shoe bottom. The cement may be applied to 70 the entire flesh side of the lining or preferably it may be applied only to that portion of the flesh side which has not already been coated with the stiffening solution, as shown in Fig. 4, wherein the cement is indicated at 42. The cemented and 75

marginally stiffened sock lining may be inserted by hand in the usual way, the lining being thrust into the extreme toe portion of the interior of the shoe with the aid of a stick having a sharp point at its end for impaling the toe portion of the lining. The stiffened margins at and near the toe portion of the lining serve to make the lining self-sustaining and thus assist materially in the operation of inserting it into the proper position. 5 After being inserted the lining is pressed down into intimate contact with the shoe bottom by the fingers of the operator and the stiffened marginal portion of the lining helps to insure that the lining will lie smoothly in place. Moreover, 10 the lining will have no tendency to curl upwardly near its edges during the wearing of the shoe because of the stiffness of its marginal portions. The stiffened marginal portions of the sock lining will offer a very substantial amount of resistance 15 to any endwise thrusts communicated thereto by the upper and thus the sock lining will constitute an internal support for that portion of the upper which is immediately above the inturned margins thereof and will effectively prevent that 20 portion of the upper from being forced inwardly or pulled upwardly away from its desired close relation to the margin of the tread sole. The lining will function in this manner whether its entire flesh surface or only the unstiffened portion 25 thereof has been cemented to the shoe bottom. While the stiffened margin of the sock lining will resist any edgewise thrust tending to crumple or displace it, it will not be sufficiently stiff to interfere to any substantial extent with 30 the upper flexing of the shoe bottom even if the stiffened marginal portion of the lining has been cemented to the latter. On the other hand, if the stiffened margin of the lining is left uncemented to the shoe bottom in accordance with the preferred practice, the shoe bottom, as a practical 35 matter, will not be stiffened to any extent by the presence of the prepared sock lining therein.

As already mentioned, the solution employed for stiffening the margin of the sock lining penetrates into the substance of the lining nearly to 40 the grain surface thereof and in case the sock linings are to be used in shoes the uppers of which are cut away in portions adjacent to the bottoms of the shoes as, for example, in open shank sandals, it is preferred to employ in the 45 stiffening solution a coloring substance the color of which will match or harmonize with that of the upper. Thus, as the stiffening substance penetrates into the sock lining, including the edge 50 face thereof, it will color or stain the edge face. In addition, the fibers of the leather at and near the edge of the lining will be consolidated as a 55 result of the stiffening or binding characteristics of the stiffening solution. Thus, the sock lining, 60 instead of having the usual uncolored raw edge which is more or less rough and fuzzy, will have a smoothly finished edge which is colored to harmonize with that of the upper so that no additional 65 finishing operations need be performed upon the edge of the lining to improve the appearance of the shoe. The application of a sock 70 lining 120, the margins of which have been stiffened and the edges of which have been colored and finished by the use of colored stiffening material, is illustrated in Fig. 8 wherein is shown a sandal comprising a tread sole 40, a heel 41, upper members 44 and 46, a heel and shank piece 48, and a sock lining 120, the edges of which have 75 been colored and finished by the use of colored

stiffening material so that smooth colored edge faces 50 are provided in the portions where the edges of the sock lining are exposed in the open shank and heel portions of the shoe. As shown, an edge binding 52 has been applied to the edges of the heel and shank piece 48 to provide a suitable finish for the latter. 5

Having described my invention, what I claim as new and desire to secure by Letters Patent of the United States is:

1. In a shoe having no insole in its forepart, a tread sole, an upper having an inturned margin secured to said tread sole in the forepart of the shoe, a sock lining of leather having a finished grain surface at its upper side and an unfinished flesh surface at its lower side, said lining having the marginal portion only of its forepart impregnated from its lower side nearly but not quite to its upper side with a stiffening substance and thereby stiffened to an extent sufficient to provide internal lateral support for the portion of the upper immediately adjacent to said inturned margin without changing the character of the marginal portion of its grain surface, the unstiffened portion of said sock lining being soft and limp so as to have no stiffening effect upon the shoe bottom, and said unstiffened portion only of the lower surface of said sock lining being secured to the shoe. 10 15 20 25 30

2. A shoe having a bottom comprising only a single layer of sole material in the forepart of the shoe, an upper having inturned marginal portions secured to said bottom and having portions cut away adjacent to said bottom, and a sock lining of soft, limp leather having an upper grain surface and a lower flesh surface and having its marginal portion only impregnated from its flesh surface nearly but not quite to its grain surface with colored stiffening material thereby providing internal lateral support for the portions of the upper immediately adjacent to said inturned portions thereof and providing a finished and colored surface at the edge of the sock lining in the localities where the upper is cut away, without however affecting the color or finish of 40 45 50 55 60 65 70 75 80 85 90 95 100 said grain surface. 30 35 40 45 50 55 60 65 70 75 80 85 90 95 100

3. A sock lining comprising a piece of soft, limp leather having a grain surface at one side and a flesh surface at the opposite side, the marginal portion only of the sock lining being impregnated from its flesh surface nearly but not quite to its grain surface with a stiffening substance whereby said marginal portion is stiffened but the grain surface is unaffected by said substance, that portion only of the flesh surface of said lining which is unimpregnated with said substance being coated with adhesive for securing the lining in place within a shoe. 50 55 60 65 70 75 80 85 90 95 100

4. That improvement in methods of shoemaking which consists in making a shoe without an insole in its forepart, providing a sock lining of soft, limp material having its marginal portion only impregnated with a stiffening substance and thereby rendered relatively stiff, applying adhesive to one side of that portion only of the sock lining which is located inwardly of said relatively stiff marginal portion, inserting said sock lining within the shoe with its adhesive treated surface facing the bottom of the shoe, and pressing the sock lining into intimate contact with the shoe bottom thereby securing the unstiffened portion only of the sock lining to the shoe. 70 75 80 85 90 95 100
